UNITED STATES PATENT OFFICE.

WILLIAM S. O'DELL, OF KANSAS CITY, MISSOURI.

JACK AND ANCHOR APPARATUS.

Application filed December 24, 1925. Serial No. 77,582.

This invention relates to apparatus for securely holding the movable crane housing of a wrecking crane in an immovable position when the same is being transported or moved from place to place.

It is well known in this art, that the heavy crane housing and the machinery contained therein, as well as the boom or crane arm, is inclined to swing around or turn upon its pivot pin unless securely affixed to the crane supporting deck. Heretofore, the tie rods or devices used to hold the crane housing from turning have broken under the strain and have been rendered useless in a large majority of the cases.

It is, therefore, one of the objects of this invention to provide a means for securely holding the swinging portion of a wrecking crane in a secured position when the same is being transported or when it is not in actual use.

A primary object of the present invention is the provision of means, carried by the ballast blocks of the crane, for engaging cooperating means carried by the crane supporting deck, whereby the movable part of the crane is held in a rigid position as well as partially supported or "jacked up".

A further object of this invention is the contemplation of means for vertically moving the movable engaging means whereby it may be lowered into the holding position to engage the cooperating deck-supported portion of the apparatus.

An even further object of this invention is to provide suitable means for holding the vertically movable portion of this apparatus in rigid engagement with the portion carried by the supporting deck.

Minor objects and refinements of construction will appear during the course of the detailed specification referring to the accompanying drawing which illustrates the preferred form of construction and which shows the jack and anchor apparatus in use with the ordinary wrecking crane of any make.

In the drawing:

Figure 1 is a plan view of the well-known wrecking crane showing the apparatus, made in accordance with this invention, in place and holding the crane housing and other movable parts in an immovable position.

Fig. 2 is a back view of the wrecking crane showing the jack and anchor apparatus in place.

Fig. 3 is an enlarged view of the device

showing the face of the same and its relation to the movable and immovable portions of a wrecking crane.

Fig. 4 is a vertical central section of the apparatus showing the means for raising and lowering the vertically movable part, as well as the means used in locking the movable part to the deck supported immovable portion.

Fig. 5 is a cross section of the device taken on line V—V of Fig. 4, and,

Fig. 6 is a bottom plan view of the movable member of the device.

With reference at this time to the drawing in detail, wherein similar reference characters refer to like parts throughout the several views, the numeral 7 designates the ordinary supporting deck of a wrecking crane which supports the crane housing 8 and boom 9. As is well known, the crane proper is equipped with ballast blocks 10 which, in this instance, are shown to be located at the back of the housing 8.

To keep housing 8 and boom 9 from turning around its pivot pin 12 while the same is being transported, it is desired and necessary to provide means for securing the movable parts to the supporting deck 7. It is also desirable to provide a means for partially supporting the weight of the crane at the same time.

Accordingly, the ballast blocks 10, which are usually positioned at each corner of the back of housing 8 are provided with an opening 13 into which is slipped a vertically movable member or block 14. The depth of opening 13 is sufficient to allow the same to completely receive block 14 when the same is raised to the inoperative position and the crane is not being held.

It is desirable to secure the movable housing and boom 8 and 9 respectively when facing either end of the supporting deck 7. To carry out this feature, there is provided an engaging means at each corner of the deck. These members are fixed rigidly to supporting deck 7 and consist of a body 15 having a downturned portion 16 which engages the sides of deck 7 as shown in Figs. 3 and 4. These members should be rigidly affixed to the deck through the use of lag screws or the like 17, and an anchor lug 18 may be provided integral with portion 16 to which is affixed a guy 19. This guy connects and aids in holding boom 9 in a rigid position.

When the device is in the holding or operating position, member 14 engages body 15 of the deck supported element, and sides 20 of body 15 extend entirely around member 14, which has a part 21 extending downwardly therefrom to enter cavity 22 formed in body 15.

To secure block 14 and lock the same in place after it is lowered, pin 23 is slidably mounted in body 15 to engage and disengage transverse opening 24 formed in part 21 of block 14. A spring 25 resiliently maintains the pin in the engaging position, and it is only necessary to pull outwardly thereon when block 14 is to be raised.

In so connecting ballast blocks 10 and deck 7, it is obvious that no swinging movement of the movable parts of the crane is allowed. Block 14 may be as thick as desired, and the parts all made strong enough without making a bulky apparatus.

As was hereinbefore mentioned, it is desirable to take some weight off of the ordinary supports of the crane by jacking it up slightly during transportation.

The means for doing this has been combined with the means for raising and lowering block 14. This means may, though not necessarily, include a screw 25 affixed into the block 14 by a set screw or other means 26. Screw 25 extends downwardly from the top of cavity 13 and into block 14 through the opening 27 to pass through a worm pinion 28 which is screwthreaded thereon. This pinion 28 is movably housed in block 14 to raise and lower the same by bearing against shoulder 29. To turn pinion 28, a worm 30 should be provided in mesh therewith which is operated by any suitable means such as a handle 31, placed in engagement with the squared end 32.

Obviously, when worm 30 is turned, gear 28 will be turned about screw 25 and be caused to ride upwardly or downwardly according to the direction of turn of worm 30.

In this manner, the block and screw 14 and 25 respectively become a lifting jack bearing downwardly against body 15 and upwardly against ballast block 10.

To hold worm 30 in a fixed position after the block 14 is raised or lowered, a slidably mounted locking yoke 33 may be provided which engages the squared end 32 as shown in Fig. 3.

Many modifications may be made in the construction of this invention without departing from the spirit of the appended claims.

What I claim and desire to secure by Letters Patent is:

1. In a jack and anchor apparatus of the class described, a movable member carried by the movable portion of a crane, means carried by the crane supporting deck for re-

ceiving one end of the movable member and co-acting means including a longitudinally movable pin for locking said movable member against movement in one direction. 65

2. In a jack and anchor apparatus of the class described, a movable member carried by the movable portion of a crane, means carried by the crane supporting deck for receiving one end of the movable member and apparatus carried by the receiving means adapted to be yieldably held in a position to 70 lock the movable member against movement in one direction. 75

3. In a jack and anchor apparatus of the class described, a movable member carried by the movable portion of a crane, a co-acting member carried by the crane supporting deck adapted to receive one end of the movable member and means housed within the movable member and operable from exteriorly thereof for moving the same 80 into and out of engagement with said co-acting member. 85

4. In a jack and anchor apparatus of the class described, a movable member carried by the movable portion of a crane, a co-acting member carried by the crane supporting deck adapted to receive one end of the movable member, means for locking said movable member against relative movement in any direction carried by said co-acting member, means housed within the movable member for moving the same into and out of engagement with said co-acting member and means for locking the moving means against movement. 90 95 100

5. In a jack and anchor apparatus for wrecking cranes, a vertically movable member carried by the ballast block of said crane, means carried by the crane supporting deck to be engaged by said vertically movable member and means for raising and lowering said movable member into and out of engagement with said deck supported engaging means, said means having a block locking means carried thereby and a flange for engaging the sides of said block whereby the block is rigidly secured against movement. 105 110 115

6. In a jack and anchor apparatus for wrecking cranes, a vertically movable member carried by the movable portion of said crane, means carried by the crane supporting deck to be engaged by said vertically movable member, means for raising and lowering said movable member into and out of engagement with said deck supported engaging means and means carried by said deck supported engaging means for locking said vertically movable member against vertical or horizontal movement. 120 125

In testimony whereof I hereunto affix my signature.

WILLIAM S. O'DELL.
